Fig. 9

Fig. 10

Fig. 11

FIG. 1 is a top plan view of an audio visual display unit housing or similar article, showing one form of my new design with the cover closed wherein the loudspeaker grille is round;

FIG. 2 is a front elevational view of the form shown in FIG. 1;

FIG. 3 is a bottom plan view of the form shown in FIG. 1;

FIG. 4 is a rear elevational view of the form shown in FIG. 1;

FIG. 5 is a side elevational view of the form shown in FIG. 1;

FIG. 6 is an opposite side elevational view of the form shown in FIG. 1;

FIG. 7 is a top plan view of the form shown in FIG. 1 with the cover lifted to an upper position;

FIG. 8 is a front elevational view of the form shown in FIG. 1 with the cover lifted to an upper position;

FIG. 9 is a right side elevational view of the form shown in FIG. 1 with the cover lifted to an upper position;

FIG. 10 is a front elevational view of the form shown in FIG. 1 with the cover lifted to an upper position and the visual display element in upper position;

FIG. 11 is a right side elevational view of the form

shown in FIG. 1 with the cover lifted to an upper position and the visual display element in upper position;

FIG. 12 is a front elevational view of an audio visual display unit housing or similar article, showing a second form of my new design with the cover closed wherein the loudspeaker grille is rectangular and relatively narrow; and

FIG. 13 is a front elevational view of an audio visual display unit housing or similar article, showing a third form of my new design with the cover closed wherein the loudspeaker grille is rectangular and relatively wide.

I claim:

The ornamental design for an audio visual display unit or similar article, substantially as shown and described.
